UNITED STATES PATENT OFFICE.

BENGT M. W. HANSON, OF HARTFORD, CONNECTICUT.

METAL-WORKING MACHINE.

1,231,255.

Specification of Letters Patent. Patented June 26, 1917.

Application filed October 9, 1914. Serial No. 865,855.

To all whom it may concern:

Be it known that I, BENGT M. W. HANSON, a citizen of the United States, residing at Hartford, in the county of Hartford and 5 State of Connecticut, have invented certain new and useful Improvements in Metal-Working Machines, of which the following is a specification.

This invention relates to metal-working machines. My improvements in whole or in part can be incorporated in various kinds of metal-working machines. In the drawings accompanying and forming part of the present specification I have shown in detail one 10 of the several convenient forms of embodiment of the invention, which to enable those skilled in the art to practice the same will be set forth fully in the following description. I do not restrict myself to this showing; I may depart therefrom in several respects within the scope of the invention defined by the claims following said description.

In this particular showing, however, the 15 improvements are shown as incorporated in a milling-machine. One of the primary purposes in view is the provision of effective means whereby a carrier for the work or otherwise can be driven either reciprocally or otherwise at different speeds. Another object is the provision of means for automatically changing at desired times the speed of movement of the carrier or equivalent element. The machine involves many 20 other features of novelty and utility, which with the foregoing will be set forth at length in said description.

Referring to said drawings:

Figure 1 is a front elevation of a metal- 25 working machine involving my invention.

Fig. 2 is a side elevation as seen from the right in Fig. 1, partly in section with the head-stock, foot-stock and gear-case removed.

Fig. 3 is a rear elevation of the machine with the two stocks removed and with the gear-case in section.

Fig. 4 is a horizontal sectional top plan 30 view of the rear portion of the machine and said gear-case.

Fig. 5 is a top plan view of a portion of the work-carrier, tool and work, depending stud and a part of the cam, the latter being shown by dotted lines.

Fig. 6 is a view partly in elevation and

partly in vertical section of the elements shown in Fig. 5.

Fig. 7 is a front elevation partly in section, of a disk and a controlling-lever.

Fig. 8 is a diagrammatic view illustrative of said disk, two controlling levers, a cam drum and the traveling work carrier. 60

Fig. 9 is a detail view partly in vertical section, of a portion of the driving mechanism. 65

Fig. 10 is a view in top plan also partly in section, of means whereby the work-carrier can be manually adjusted.

Like characters refer to like parts throughout the several figures, which it will be noted 70 are on different scales.

The various parts of the machine may be sustained by any suitable framework, that shown for such purpose comprising the base or bed 2. Supported by said base or bed is 75 a suitable carrier such as 3 (see for instance Figs. 1 and 2) and which as illustrated consists of a slide mounted for reciprocation upon the top of the base or bed, the latter as represented being provided with guide- 80 ways 4 to receive the depending tongue 5 of the reciprocatory carrier or slide 3 to which in the present case the work is connected, the tool (or tools) being supported independently of the carrier. This carrier may 85 be reciprocated in any desirable manner, and in addition to this can be driven at different speeds, for example fast and slow, the organization being such in preference, that the carrier can be operated as may be 90 desired, for example it may be initially given a fast movement, then a slow and then a fast or these relations may be entirely changed, the possibilities of speed-control being practically unlimited. 95

I prefer to effect the reciprocation of the work carrier by a cam-drum. This condition can, of course, be obtained in other ways, but the best results are obtained by using the medium mentioned which by preference always turns in the same direction. A cam-drum such as 6 (Fig. 2) answers satisfactorily my requirements, said cam drum as illustrated being fastened to the shaft 7 within the hollow base or bed 2. As illustrated said shaft 7 is supported for rotation by the front and rear walls of the base or bed, and for a purpose that will hereinafter appear, projecting through the front wall of said base. This shaft 7 as will also here- 100 105 110

inafter appear is continuously rotative and as I have practically already observed, always turns in the same direction. When I speak of the shaft as being "continuously rotative," I mean while the machine is in action. This drum 6 has a peripheral race or groove 8 (Fig. 2) formed for instance by the duplicate projections 9, said groove 8 receiving the stud 10 depending from the work-carrier or slide 3. Said cam-groove may be considered as comprising two similar spiral portions 11 and 12, the terminals of which coincide or register. The spiral portion 11 acts to move the work-carrier or slide 3 forward, while the spiral portion 12 serves to reverse the carrier or to return it to its primary or initial position, the forward stroke of the work-carrier or slide being identical in degree with the rear stroke and each being of considerable amplitude, so as to permit an attendant to freely connect work with the carrier 3 when in its backward or retracted position, and this without possibility of interfering with the cutter or other tool. When the depending stud 10 (preferably in the form of an anti-friction roller) is at the rear junction of the two spiral portions 11 and 12, the work-carrier or slide 3 is in its primary position and in readiness to have the work connected therewith. As soon as the machine is thrown into action, the stud 10 is caused to relatively traverse the spiral portion 11 to thereby advance said work-carrier or slide, the advancing movement continuing until the stud 10 enters the forward end of the spiral portion 12 at which point the carrier is reversed, the return movement continuing as the stud 10 relatively traverses the spiral portion 12 until said stud reaches the rear junction of the two spiral portions at which point as will hereinafter appear movement of the work carrier or slide is stopped automatically.

It will, therefore, be evident that on each full turn of the cam-drum 6, the work carrier or slide 3 is given one complete reciprocation, and as I have already intimated, the forward movement may be fast and the rear slow or vice versa, while on the forward movement the carriage may be successively speeded up and down and the same on the return movement. Preferably, however, this variation in speed is not obtained through the primary influence of the cam-drum. This cam-drum naturally, however, is operated at a variable speed or at least may be, because there may be cases where I should prefer that the reciprocation of the work-carrier throughout its entire movement be slow, or on the contrary that it be a rapid one. The means shown for effecting such speed control of the cam-drum 6 and therefore of the work-carrier 3 will be hereinafter set forth.

The work carrier or slide 3 moves in the channel 13 in the upper side of the base or bed 2. At one side of the channel 13 (the left in Fig. 1) is mounted the head-stock 14, while at the opposite side of said channel is situated the foot-stock 15, said head and foot stock being usually clamped rigidly to the bed 2 and as will be understood, the work-carrier traveling back and forth between them. On the front of the head-stock 14 is mounted the slide 16 having suitable bearings for the spindle 17 of the tool 18 which is shown as being of "milling" type, the work to be milled or otherwise operated upon being held in the clamp denoted in a general way by 19 suitably fastened to the reciprocating carrier 3. The milling cutter 18 is usually directly connected with the arbor or mandrel 20, the spindle 17 having a collet or chuck 21 to receive one end of said arbor, the opposite end thereof fitting a socket in the auxiliary spindle 22, carried by the slide 23 on the foot-stock 15 as is somewhat common in milling-machines. The slides 16 and 23 as shown are vertically adjustable to vary the elevation of the main and auxiliary spindles 17 and 22, and for this purpose any desirable means may be provided, for example the feed screws 25 and 26 furnished as shown, with hand-wheels 27 and 28, the slides having fixed nuts to receive the respective screws as also quite common in the metal-working art. On the outer side of the head stock 14 is supported the change gear box 29, inclosing the change gearing 30 and the final gear of 100 which is rigid with the spindle or shaft 17. The primary element of said change gearing 30 is fastened to the shaft 31 having fastened to it the pulley 32 driven by a belt 33. Fastened in some suitable manner to the rear of the bed 2 (Fig. 4) is the box or case 40, screws 41 being shown as a suitable means for mounting said box rigidly in place. Extending entirely through this box 40 for example at the top thereof is the 110 rotary shaft 42 having fastened to it a drum 43 connected by the belt 42' to the pulley 43' fastened to the shaft 31 (Fig. 9), said belt 42' between its ends passing over the guide pulleys 42''. Located below and 115 in parallelism with the shaft 42 is the shaft 44, the two shafts as shown being connected by a train of change gears denoted in a general way by 45. This shaft 44 is sustained by a bearing upon and extends into the box 120 40. Fastened to the shaft 42 inside the box 40 is the pinion 46 in mesh with the spur gear 47 loose on the shaft 48, situated within and supported by the box 40. This spur gear 47 has an inwardly elongated hub 49 125 to which is pinned or otherwise secured the clutch member 50 co-operative with the clutch member 51 splined or otherwise suitably associated with the elongated hub of the bevel pinion 52, for sliding movement on 130

said hub, it being evident that the clutch member 51 can be shifted into and out of power transferring relation with the clutch member 50. When they are out of engagement 5 the bevel pinion will not be turned. The means shown for shifting the clutch member 51 will be hereinafter described. The bevel pinion 52 is in mesh with the bevel gear 53 pinned or otherwise suitably 10 fastened to the rear member of the sectional shaft 54, the sections of said shaft 54 being coaxial and as shown the rear section thereof having a reduced portion 55 fitting a socket in the front portion to maintain the sections 15 of said shaft 54 coaxial. The two sections of said shaft 54 are adapted to be clutched together, being in fact normally in this relation and the front section is operatively connected with the cam-drum 6. I might 20 observe at this time that the bevel gear 53 constitutes in the organization shown the primary element of quick-driving mechanism, the primary element of slow-driving mechanism being as shown, the worm gear 25 56 hereinafter more particularly described. The shaft 44 has rigidly fastened to its inner end the pinion 57 in mesh with the spur gear 58 loose on the shaft 59 mounted within and supported by the sides of the box 40. 30 Splined or otherwise suitably secured to the hub of the spur gear 58 for sliding movement thereon and rotation therewith is the clutch-member 60 co-operative with the clutch member 61 pinned or otherwise suitably 35 secured to the shaft 59. When the clutch members 60 and 61 are out of engagement the shaft 59 will not be rotated, but when they are in working relation the opposite result follows. The shaft 59 is shown 40 provided with a worm 62 in mesh with the teeth of the worm gear 56 loose on the shaft 54, which worm gear through the described connections, is driven at a lower speed than the bevel gear 53. 45 The bevel gear 53 and worm gear 56 are adapted to be clutched together, and this clutch may vary decidedly as to character, although one of "pawl-and-ratchet" type has been found to be quite satisfactory. 50 The pawl-and-ratchet mechanism may be mounted in any desirable manner, although in the present case the ratchet 63 is rigid with the worm gear 56, being fastened by screws 64 and pins 65 to that face of the 55 worm gear 56 adjacent the bevel gear 53. As shown the bevel gear is provided near its periphery (Fig. 3) with several pawls 66 pivotally mounted in place, there being as shown four of such pawls, and their 60 teeth being constantly advanced by springs as 67 acting against the tails of said pawls. By employing a number of pawls with a single ratchet-wheel I can make the teeth of the ratchet wheel as much larger than 65 if I employ a single pawl as is the multiple

of the pawls, provided the pawls be properly positioned, and this multiple in the present case is four. That is to say by employing four pawls I can make the ratchet wheel teeth four times the strength they 70 would be if I utilized but a single pawl, which is a feature of considerable importance. The number is not an essential matter, although that shown has been found quite satisfactory. The pawls are not equidistantly spaced but are so set as to engage coöperating teeth at different points, the construction, however, being such that there will always be a pawl practically behind and against the base of a ratchet tooth so as to 80 provide against loss of time during the slow feed of the work-carrier or slide 3. In Fig. 3 the pawl at the left is shown behind and against the base of a coöperating tooth, the pawl at the top being one fourth the distance along its tooth. The pawl on the right is shown one half the distance along its tooth, while the pawl at the bottom is shown three-fourths of the distance along its tooth. It will be understood that when 90 the quick or rapid feed mechanism is in action, this is accomplished through the primary agency of the bevel-wheel 53, the clutch members 50 and 51 at this time being in engagement. It is conceivable and 95 more than likely that the clutch members 60 and 61 will be in engagement at the same time, thus causing the rotation of the worm gear 56. The worm gear, however, operates at a much lower speed than the bevel 100 gear 53, so that relatively the teeth of the pawls 66 traverse the teeth of the ratchet wheel 63 idly or without accomplishing anything. Should the clutch member 51, however, be disengaged from the clutch 105 member 50, the rotation of the bevel-gear 53 by the bevel-pinion 52 will be stopped, but the worm gear 56 will continue to rotate owing to the engagement of the clutch members 60 and 61 and as it does so, one of 110 the pawls 66 by engaging the ratchet 63 will rotate the bevel gear 53 through the agency of the worm gear 56 thereby through the described mechanism rotating the drum 6 through the connections hereinafter described, slowly and necessarily effecting 115 a correspondingly slow movement of the work-carrier.

While preferably the machine is initially thrown into action by hand as will herein-after appear, the changes in speed or velocity of the work-carrier 3 are preferably automatically accomplished, for example through the shifting of a plurality of controlling members such as levers which control the action of clutches or analogous devices such, for instance as the clutch members 51 and 61 to which I have already referred.

Referring now for example to Figs. 2 and 130

4, it will be seen that within the box 40 is a bearing 68, constituting a support for the three-armed rocker 69 pivoted to said support as at 70. The intermediate arm 71 of 5 said rocker 69 is forked to straddle the clutch member 51, the branches of the fork having studs 72 to enter the circumferential channel of said clutch member 51 thereby as the rocker 69 is oscillated to shift said clutch member into and out of power transferring 10 relation with the clutch member 51. The arm 73 of said rocker has pivoted to it the extreme rear end of the rod 74 likewise connected at its forward end to the crank 75 15 fastened to and rising from the shaft 76 supported for oscillation on the bracket 77 on the front of the bed 2. To said shaft 76 is fastened the lower end of the lever 78 shown as occupying its retracted position in 20 Fig. 2. When said lever is in this position the clutch member 51 is disengaged from the clutch member 50. The initial forward movement of the lever 78 is effected by hand, but the final movement is rapidly secured 25 by independent means, excellent results having been obtained in this connection through the agency of a spring. The arm 80 of the rocker 69 is bored to receive the spring-plunger 81 constantly urged forward by the 30 spring 82, the forward or outer end of said spring 82, the forward or outer end of said spring plunger being beveled to coöperate with the stationary wedge 83 mounted within the box 40 and usually made rigid with the bottom thereof. In Fig. 4 the clutch 35 members 51 and 50 are out of engagement. At this time the wedge end of the spring plunger 81 is against the outer face of the wedge 83. As the lever 78 (Fig. 2) is advanced as will hereinafter appear, the rod 74 40 and arm 73 are moved rearward, while the arm 80 is moved inward, thus causing the bevel plunger 81 to ride along the outer bevel face of the wedge 83 and hence causing said plunger to enter its bore and coming 45 press the spring 82, the tip of the plunger passing the tip of the wedge just about the time the teeth of the clutch member 51 meet the teeth of the clutch member 50 which latter condition was brought about as the 50 arm 71 swung to the right (Fig. 4) on the described movement of the rod 74. When the wedge-like plunger crosses the apex of the wedge 83, the spring 82 is free to expand and as it does so, it imparts to the arm 71 55 an accelerated further movement to the right (Fig. 4) to bring the clutch member 51 into full clutched relation with the supplemental clutch member 50 which results in throwing into action the quick feed mechanism for the 60 work carrier 3.

Mounted adjacent and in rather comparative close proximity to the lever 78 is a somewhat similar lever 85 fastened to the shaft 86 also sustained by said bracket 77. 65 With said shaft 86 is rigid the crank arm 87

to which is pivoted the rod 88 joined at its rear end to the outer branch of the three-armed rocker 90 which is an exact counterpart of the rocker 69. The intermediate arm of this rocker 90 is forked and the 70 branches of its fork have studs 91 to enter the peripheral channel of the shiftable clutch member 60 while the inner branch has a spring plunger 92 coöperative with the fixed wedge 93 on the bearing 94 in the box 40. 75 When the lever 85 is swung toward the right the rod 88 is moved to the rear so that its intermediate arm can be swung over first by hand and thereafter by the spring of the plunger 92 in the manner exactly as described, to cause the clutch member 60 to engage the clutch member 61 and thereby as set forth cause the rotation of the worm 56. When both levers are thrown forward or to the right in Fig. 2 both the quick and slow 80 speed mechanisms are thrown into action, but the slow speed mechanism accomplishes nothing until the quick speed is thrown out of operation.

As will be inferred the two levers 78 and 90 85 can be operated by hand, although the quick feed controlling lever 78 is normally under lock as will hereinafter appear. In addition to this the two levers are automatically operated through means movable 95 with the carrier 3 and the disk 95 equipped with one or more dogs, cams or equivalent means acts satisfactorily in this connection. Said disk 95 constitutes a cam, being rigidly fastened in some desirable manner to the 100 forward end of the cam drum shaft 7 from which it will be clear that said disk 95 rotates in unison with the cam drum 6.

The effects of the quick and slow feed mechanisms, as will be understood, are applied to the sectional shaft 54, the sections of which during work are normally clutched to each other, as will hereinafter appear. To the inner or front section of said shaft 54 is connected a pinion 54' in mesh with the 105 spur gear 55' rigid with the cam drum shaft 7 as shown for instance in Figs. 2 and 4. It, therefore, follows that as the speed of the shaft 54 varies the speed of the shaft 7 and hence of the drum 6 through the intermediate 110 described connections will be correspondingly changed so as to regulate the feed of the reciprocating carrier 3.

In the diagrammatic Fig. 8 I have shown the disk or cam 95, the carriage reciprocating drum 6, the stud 10, the two levers 78 and 85 and certain coöperating devices including a series of dogs 96, 97, 98, 99, 100 and 101 on the disk 95. These dogs, cam members or tappets 96 to 101 (except the 125 dog 97) are not only removably mounted, but are adjustable to vary their points of action against the respective levers 78 and 85. This Fig. 8 shows one complete cycle of movement of the parts and in it the arrows 130

indicate the direction of travel of the respective parts. As shown in Fig. 7 these dogs straddle the periphery of the disk 95 and are (except the dog 97) adjustable circumferentially of said disk. They may be held in their adjusted positions by screws as 102 adapted to enter the annular groove 103 near the periphery of said disk 95. The dog or cam 97 is the primary or master cam, 10 and in the present instance as virtually stated, is not adjustable; it may be held rigidly in position by a pin, rivet 104 or in some other suitable manner. Referring again to Fig. 8 the two levers 78 and 85 are 15 shown as occupying their operative or shifted positions or that they assume when the quick and slow feed mechanisms are thrown into action, although when they are thus shifted, the slow feed mechanism is 20 accomplishing nothing, being operative only when the lever 78 is in its initial position as shown in Fig. 2 for example. The two levers as may be inferred are automatically moved from their shifted to their original 25 positions by the dogs or cams 96 to 101 inclusive, and for this purpose they may be provided with pins or studs 105 and 106 to be engaged by said dogs. Said levers can also be operated by hand. Both pins 105 30 and 106 are yieldingly mounted; I will hereinafter describe the mounting of the pin 105 which is exactly like that of the pin 106. The dog 96 is provided with an active surface 107 shown as beveled. It will be assumed that the parts are shown in the positions represented in Fig. 8; as a consequence the work carrier 3 will be fed at its high speed. As the disk 95 rotates this beveled surface 107 will strike the pin 106 and shift 35 the lever 85 to its original position, said lever through the rod 88 and connections described moving the clutch member 60 out of engagement with the clutch member 61. The master dog or cam 97 has two opposite 40 bevel surfaces 108 and 109. As the disk 95 continues to rotate, the bevel surface 108 will act against the pin 105 in such manner as to return the lever 78 to its initial position, whereby said lever on such movement 45 can through the rod 74 and intermediate described connections, disengage the clutch member 51 from the clutch 50 and wholly arrest the movement of the work-carrier 3. When the work-carrier 3 comes to a state of 50 rest, the pin 105 will be against the wedge or bevel surface 108 near the outer end thereof and the wedge or bevel surface 109 on the final part of the movement of the cam disk 95 will engage the pin 106 and 55 slightly shift said lever 85 but not sufficiently to effect through the described connections, the engagement of the clutch member 60 with the clutch member 61. This cam or dog 97 presents a convenient means 60 for locking the lever 78 normally against shifting movement, it being understood that the pin 105 is normally against the bevel surface 108 between the ends thereof and at the same time that the bevel surface 109 is against the pin 106. It will be evident that 70 when the pin 105 is against the bevel surface 108, the lever 78 cannot be shifted unless the pin 105 be disengaged from said bevel surface 108 or what is the same thing the cam dog 97 of which said bevel face forms a 75 part. The pin 105 (Fig. 7) as shown is slidingly fitted within the sleeve 110 which extends freely through counterbored opening 111 near the upper or outer end of the lever 78, the outer end of said sleeve 110 80 being closed by the thimble 112 which is threaded into said sleeve 110 and which virtually forms a rigid part thereof. Between the thimble 112 and the pin 105 is interposed the coiled spring 113, the thimble 85 and pin being bored to receive the terminal portions of the spring which acts to yieldingly back up the pin 105. The sleeve 110 constitutes a convenient carrier for the pin, being in itself yieldingly mounted, being 90 circumferentially reduced to present a shoulder 114, the circumferentially reduced portion being surrounded by the coiled push spring 115 bearing against said shoulder and also against an abutment consisting in 95 the present case of the inner wall of the counterbored portion of the hole or opening 111, the spring 115 exerting a constant tendency to advance the sleeve or carrier 110 and necessarily the yieldingly mounted pin 100 105 associated therewith.

Pivots supported between its ends near the handle end of the lever 78 is the short lever 117. As a matter of fact the upper branch of said lever 117 can be grasped at 105 the same time that the handle of said lever 78 is. The lower branch of the short lever 117 is forked to fit the annular groove 118 in the thimble 112. When the operator grasps the handle of the lever 78 to move 110 the same forward, or to the right in Fig. 8 the palm of his hand or some other part thereof will press the upper or long branch of the short lever 117 inward and the lower or short branch outward, thereby retracting the sleeve 110, and as a consequence the pin 105 so that the pin will be carried free of the cam or dog 97, the lever 78 as a consequence being released by the cam or dog 97, so that it can be swung forward to throw 120 the high speed mechanism into action in the manner already described. As soon as the lever 78 is shifted the disk 95 commences to rotate also in the manner set forth and as said disk turns the bevel face 109 rides 125 against the pin 106 and shifts the lever 85 to throw the clutch member 60 into clutched relation with the clutch member 61. It will be assumed that the disk is being rotated (Fig. 8); when it has moved a certain dis- 130

tance the bevel surface 119 of the dog 98 will ride against the pin 105 to return the lever 78 to its initial position, said lever 78 on such movement through the described 5 parts disengaging the clutch member 51 from the clutch member 50, the clutch member 60, however, still being in engagement with the clutch member 61, so that as a consequence the work carrier will be driven 10 at its low speed. Subsequent to this point the bevel surface 120 of the cam or dog 99 will act against the pin 105 to again shift the lever 78 and throw the high speed mechanism into action. Following this the bevel 15 surface 121 of the dog 100 will engage the pin 105 to stop the quick speed, the slow speed, however, still remaining in action. The bevel surfaces 122 will then engage the pin 105 and again shift the lever 78 to throw 20 in the high speed feed mechanism beyond which point the bevel surface 107 will engage the pin 106 to return the lever 85 to its primary relation, this continuing until the bevel surface 108 engages the pin 105 25 to return the lever 78 to its initial position and thereby stop the feed. The dogs in question may be increased or decreased as will be inferred. In Fig. 8 I have shown by dotted lines a dog 123 just like the other 30 dogs and which has bevel surfaces 124 and 125 to simultaneously return the two levers 78 and 85 from their shifted to their original positions.

It will be noticed that the auxiliary dogs 35 96 and 98 to 101 inclusive and the dog 123 extend out from the periphery of the disk 95 a greater distance than the master or primary dog 97. Some of these auxiliary dogs act to return the lever 78 from a shifted 40 ed to an initial position. The object of this difference in extent between the auxiliary dogs and the main or master dog is this: The lever 78 is initially shifted by hand by the retraction of the pin 105. It is possible 45 that an attendant may inadvertently hold the lever 117 in its shifted position; in this event the dog which should return said lever to its original position will engage the pin 105, notwithstanding the fact that said pin 50 may be in its retracted position, and knock the lever 78 out of the operator's hand and return the same to its primary position.

During normal operation of the machine the sections of the shaft 54 are connected 55 rotatively with each other, and for this purpose a clutch may be utilized (see for example Figs. 2 and 4). This clutch consists of sections 130 and 131, the section 130 being connected with the rear section of said 60 shaft by pinning or otherwise, while the clutch section or member 131 is splined to the forward or front section of said shaft. In both Figs. 2 and 4 the members or sections 130 and 131 are clutched together, by 65 virtue of which when the rear shaft section

54 is driven through the intervention of either the quick or slow feed mechanism the rear section of said shaft 54 will be rotated to effect the turning of the drum 6 and consequently of the cam disk 95.

70

I provide means of a suitable character to effect the adjustment of the work carrier 3 by hand, and the following mechanisms answer satisfactorily in this connection. Slidably supported within the base or bed 2 is the rod 132 rigidly having fastened to its rear end the forked element 133, the branches of which have studs 134 fitting a circumferential channel in the clutch member 131. Pivoted to the forward end of 75 said rod 132 is the crank arm 135 fastened to the shaft 136, the crank arm 135 being inclosed in the bed 2. Fastened to the shaft 136 exteriorly of the bed 2 is the hand lever 135' shown as occupying its normal position 80 in Fig. 2. When the hand lever 135' is swung to the right in Fig. 2 the clutch member 131 through the described parts will be disconnected from the clutch member 130 thereby throwing the drum 6 out of operative relation with the power driven or rear section of the shaft 54. Connected with the forward section of the shaft 54 (Fig. 10) is 85 a spur gear 137 in mesh with a spur gear 138 rigid with the shaft 139 supported with in the base or bed 2. Rigid with the spur gear 138 is the bevel gear 140 in mesh with the bevel pinion 141 at the inner end of the stub shaft 142 supported by said bed 2, the two bevel gears being within the bed. The 90 outer or extended end of the shaft 142 is shaped by being squared or otherwise as at 143 to receive a hand crank. To adjust the work carrier or table 3 the clutch member 131 will be disconnected from the clutch 95 member 130 by the operation of the lever 135' in the manner already described after which the hand crank will be connected with the squared end 143 of the stub shaft 142. The shaft 142 can then be rotated to effect 100 105 through the described gearing the rotation of the forward section of the shaft 54 and through the latter and the described gearing the rotation of the shaft 7 and cam drum 6 and necessarily the movement either forward or backward of the work carrier 3.

The tappets or cam members 97, 120 and 122 are provided upon their outer surfaces with rearwardly beveled faces 150, 151 and 152 respectively, the function of which will 110 120 now be explained. As I have set forth there are times when the work carrier 3 should be adjusted manually, and in accomplishing this office the disk 95 is sometimes turned forward and at other times turned backward. These beveled surfaces 150, 151 and 152 respectively are adapted to strike one or the other of the yieldingly mounted pins 105 and 106 causing the pins to move outward, and in this manner the backward ad- 125 130

justment of the disk 95 can be accomplished without doing any injury. It will be remembered that I have stated that the two pins 105 and 106 are similar in mounting. 5 I might state that while the pin 105 is provided with an operating lever as 117, there is no occasion for such an operating lever in conjunction with the pin 106.

It is important that the speed of the reciprocal or slidable work carrier 3 be reduced during milling or equivalent action approximately coincident with the reverse in movement of said carrier; that is to say at practically the conclusion of the advance 15 and the commencement of the retraction of said carrier, by virtue of which the milling or equivalent tool is prevented from injuring the work. This result I can obtain in various ways, although the cam 6 has been 20 found very satisfactory in this respect, the movement of the carrier being perceptibly reduced at about the time the stud 10 leaves the spiral portion 11 and enters the spiral portion 12 as shown in Fig. 5. This slow- 25 ing down in movement of the carrier 3 at the time indicated occurs when either the high or low speed feed mechanism is in action. When the slow feed mechanism is in 30 operation, it will be evident that substantially at the point of reverse the speed of the carrier is further reduced.

What I claim is:

1. In a machine of the class described, the combination of a power transferring member, a second power transferring member having a constant clutch connection with the first power transferring member, means for driving the first power transferring member at a greater speed than the second power 35 transferring member and for stopping them both at predetermined points, and a movable member having a driving connection with the first power transferring member.
2. In a machine of the class described, the 40 combination of a reciprocal carrier, a power transferring member having a driv-

ing connection with the carrier, a second power transferring member having a constant clutch connection with the first power transferring member, and means for 50 rotating the power transferring members at different speeds.

3. In a machine of the class described, the combination of a traveling carrier, a power transferring member having a driving connection with said traveling carrier, a second power transferring member having a pawl and ratchet constant clutched connection with the first power transferring member, and means for driving the power transfer- 55 ring members at different speeds. 60

4. In a machine of the class described, the combination of a traveling carrier, means involving quick and slow speed mechanisms for reciprocating the carrier, levers for independently controlling said mechanisms, and a rotary disk provided with a series of peripheral dogs having beveled portions disposed in opposite directions, the levers having pins engageable by the beveled portions 65 70 as the disk rotates to move the levers oppositely, certain of the dogs extending outward from the periphery of the disk a greater distance than another dog.

5. In a machine of the class described, the combination of a traveling carrier, means involving quick and slow speed mechanisms for operating the carrier, independently active levers for automatically controlling said mechanisms, and a rotary disk provided 75 80 with peripheral dogs, the levers having pins engageable by said dogs to shift the levers, one of the dogs being initially disposed in the path of one of the pins, and means for retracting said last mentioned pin. 85

In testimony whereof I affix my signature in presence of two witnesses.

BENGT M. W. HANSON.
